(57) **CLAIM**

The ornamental design for a power module, as shown.

DESCRIPTION

FIG. 1 is a perspective view of the power module of the present invention;

FIG. 2 is a front view of the power module of the present invention;

FIG. 3 is a back view of the power module of the present invention;

FIG. 4 is a left side view of the power module of the present invention;

FIG. 5 is a right side view of the power module of the present invention;

FIG. 6 is a bottom view of the power module of the present invention; and,

FIG. 7 is a top view of the power module of the present invention.

1 Claim, 3 Drawing Sheets

FIG. 2

FIG. 3

FIG. 4

FIG. 5

FIG. 6

FIG. 7

Disclaimer and Dedication

D. 463,362 — Raul Alcantar, Plano, TX (US); Gordon K. Y. Lee, Plano, TX (US); Victor Ke-Ji Lee, Plano, TX (US); Carl Milton Wildrick, Parker, TX (US). POWER MODULE. Patent dated September 24, 2002. Disclaimer filed September 23, 2015, by the assignee, TDK-Lambda Corporation.

Hereby disclaims and dedicates to the Public, the remaining term of said design patent.
